UNITED STATES PATENT OFFICE.

OSCAR WOODWARD, OF BABYLON, NEW YORK, ASSIGNOR TO REMINGTON TYPEWRITER COMPANY, OF ILION, NEW YORK, A CORPORATION OF NEW YORK.

FAN-FOLD WEB.

Application filed September 15, 1923. Serial No. 662,794.

To all whom it may concern:

Be it known that I, OSCAR WOODWARD, citizen of the United States, and resident of Babylon, in the county of Suffolk and State of New York, have invented certain new and useful Improvements in Fan-Fold Webs, of which the following is a specification.

My invention relates to continuous fan-fold webs used in typewriting machines. An example of a typewriting machine especially designed for use with such fan-fold webs is disclosed in the patent to Arthur W. Smith, No. 1,287,123, dated December 10, 1918. In use in such machines carbon sheets are inserted between the plies of the fan-fold web for the production of manifold copies when the "original" is written. The use of a fan-fold web has distinct advantages in that its different plies and interleaved carbon sheets may be fed through the machine together, with the superposed printed blanks and writing maintained in register, and without one ply or sheet creeping relatively to another. It has been customary to make the web from a single piece of paper folded longitudinally to form the fan-fold. A distinct disadvantage which presents itself in the use of such a web is that the quality of paper is of a uniform character throughout. If a good quality of paper is employed this makes its use expensive, since an inferior quality of paper for the office copies would suffice. If, on the other hand, an inexpensive paper is used, this presents the objection of having to send such inferior quality of paper to the customer.

By my invention I overcome these difficulties and provide a fan-fold web which has all of the advantages derived from the use of such a web, without any of the attendant difficulties. In accordance with my invention, I provide a composite fan-fold web in which different plies have different characteristics. Thus, the ply or plies on which the typewritten copies that are to go to the customer are written may be made of a comparatively superior quality of paper, whereas the plies on which the copies for office use are written may be of a comparatively inferior quality. Then, again, the customer's copy may be written on a ply of comparatively heavy stock and the manifold copies for office use may be written on compara-

tively light stock; affording better mani-folding than would be the case were all of the plies made from a comparatively heavy stock. Then, again, it may be found desirable to have the paper of the bill or filled-in blank which goes to the customer of a different color from that intended for office copies. Any or all of these results may be attained by a fan-fold web constructed in accordance with my invention.

To the above and other ends which will hereinafter appear, my invention consists in a fan-fold web constructed as set forth in the following description and particularly pointed out in the accompanying claims.

In the accompanying drawings wherein like reference characters indicate corresponding parts of the different views,

Figure 1 is a face view of a work sheet or web made in accordance with my invention and showing the sheet as it appears before it is folded into a fan-fold formation.

Figure 2 is a perspective view of the web folded and creased ready for use and with the carbon sheets inserted in place.

Figure 3 is a fragmentary perspective view of a modified form of fan-fold web constructed in accordance with my invention.

Referring to Figs. 1 and 2, it will be seen that the web as shown comprises four sections or plies 1, 2, 3 and 4, although any suitable number of such sections may be employed. The web is preferably scored, or otherwise suitably weakened longitudinally thereof along the lines 5, 6 and 7 in order that the sections may be readily separated along such lines and along the lines of the folds coincident therewith. Each section may, if desired, have a succession of forms printed thereon longitudinally of the section, and with lines *a* reading across the web. In the present instance the sections 1 and 3 have the forms printed on the exposed side of the web as it is shown in Fig. 1, whereas the sections 2 and 4 have the same forms printed on the opposite side of the web. Corresponding forms on the four sections register when the web is folded into the fan-fold formation shown in Fig. 2; the section 1 being the outermost or "original," to receive the direct imprint from the machine. Any writing produced on a form on the section 1 will be reproduced through the interleaved carbon sheets 8 in a correspond-

ing position on each of the other corresponding registering forms or sections 2, 3 and 4. Sections 2, 3 and 4 may be printed with distinguishing marks, as indicated at 5 9, to designate, for example, different departments in which the office copies are to be filed, whereas the "original" blank or bill when filled in and detached from the section 1 is to be sent to the customer. The sections 10 2, 3 and 4 may be made from a continuous web of paper of comparatively inferior quality, since the filled in blanks or bills detached therefrom are intended merely to be filed away as office copies. The section 15 1 beyond its scored line 5, overlaps a bottom side edge portion of the section 2, as indicated at 1^a, and is attached thereto, preferably by pasting the overlapping portion of the section 1 to the section 2. The section 20 1 being a separate sheet attached to the remainder of the web may be of a different character from the latter. Since the filled-in bills or blanks detached from the section 1 are the "originals" intended to be sent to 25 the customer, this section may be made from a better grade of paper, or from heavier stock, or have a different color from the remainder of the web. Or it may be desirable to include all of these distinctions in 30 this section.

In some instances it is desirable to send two filled-in blanks or bills to the customer, one of which is intended to be retained by the customer for his records and the other 35 of which is to be returned to the sender with the remittance. It may therefore be found desirable to have both copies sent to the customer made out on a better quality of paper than that used for the file or office 40 copies. In Fig. 3 I have illustrated a fan-fold sheet made to meet these requirements, and in which the first two sections 10 and 11 are made from a single web of paper of comparatively superior quality, being preferably 45 scored along the fold 12 thereof. This sheet, beyond its opposite line 13 of scoring, is extended so that it may overlap and be pasted to a side edge portion of the adjacent section 14, as indicated at 15. The 50 remaining plies or sections 16, 17 and 18 are formed integral with the section 14, all of such sections being made from a comparatively inferior grade of paper, or paper having different characteristics from the sheet constituting the plies 10 and 11. Each 55 additional fold 19, 20 and 21 in the web is preferably scored in order that the sections may be readily separated when desired. Other than as herein indicated the fan-fold 60 web illustrated in Fig. 3 may be made and used in the same manner as the web previously described.

As illustrated in Fig. 2 the web may be folded transversely at 22 where one blank is 65 to be divided from the next longitudinally

of the web, and the parts thus folded may be stacked as shown at the left-hand side of Fig. 2.

It will be understood that in accordance with my invention I not only am enabled to employ a web in which paper of different plies or layers thereof have different characteristics for the purposes pointed out, but the folded web having its different plies or layers connected together alternately at opposite side edges is of a substantially uniform thickness from side to side of the pack no matter how many plies are employed, so that it may be fed effectively through the machine. A zigzag or fan-fold sheet of this character is highly efficient in maintaining the corresponding blanks and written matter on the different sections in registration.

What I claim as new and desire to secure by Letters Patent, is:—

1. An article of manufacture comprising a fan-fold web superposed layers of which are integral and are formed from a single web of paper of a comparatively inferior quality and are detachably connected together alternately at their opposite side edges, and a web of paper of a comparatively superior quality detachably secured along one side edge to said fan-fold web and forming an outside layer of the pack to directly receive the writing from a typewriting machine.

2. An article of manufacture comprising a fan-fold web superposed layers of which are integral and are formed from a single web of paper of a comparatively inferior quality and are detachably connected together alternately at their opposite side edges, said layers having a succession of registering forms printed thereon, and a web of paper of a comparatively superior quality detachably secured along one side edge to said fan-fold web and forming an outside layer of the pack to directly receive the writing from a typewriting machine, said outside layer having a succession of forms which register with said forms on the fan-fold web.

3. An article of manufacture comprising a fan-fold web superposed layers of which are integral and are formed from a single web of paper of a comparatively inferior quality and are detachably connected together alternately at their opposite side edges, and a web of paper of a comparatively superior quality detachably secured to the fan-fold web by pasting it to the free side edge of an outermost layer of the latter, said superior quality of web forming one or more additional layers that constitute a continuation of the fan-fold formation of the first mentioned web.

4. An article of manufacture comprising a fan-fold web superposed layers of which are integral and are formed from a single web of paper of a comparatively inferior quality and are detachably connected together alter-

nately at their opposite side edges, said layers having a succession of registering forms printed thereon, and a web of paper of a comparatively superior quality detachably secured to the fan-fold web by pasting it to the free side edge of an outermost layer of the latter, said superior quality of web forming one or more additional layers that constitute a continuation of the fan-fold formation of the first mentioned web and having a succession of forms printed thereon which register with said forms on the first mentioned web.

Signed at the borough of Manhattan, city of New York, in the county of New York and State of New York, this 13th day of September, A. D. 1923.

OSCAR WOODWARD.
